OIL BURNER

Harvey C. Gore and James H. Nunn, Jr., Snyder,
Tex.; said Gore assignor to said Nunn

Application December 18, 1933, Serial No. 703,017

2 Claims. (Cl. 158—92)

The present invention relates to a burner particularly adapted for burning fuel such as distillate, gas oil or kerosene oil.

The object of the invention resides in the provision of a burner of this nature which affords proper mixture of the air with the fuel for perfect combustion.

Another very important object of the invention resides in the provision of a burner of this nature 10 which is simple and compact in its construction, thoroughly efficient and reliable in use, and otherwise well adapted to the purpose for which it is designed.

With the above and numerous other objects in 15 view as will appear as the description proceeds, the invention consists in certain novel features of construction, and in the combination and arrangement of parts as will hereinafter be more fully described and claimed.

20 In the drawings:

Figure 1 is a top plan view of a burner embodying the features of my invention.

Figure 2 is a sectional view therethrough taken substantially on the line 2—2 of Figure 1, and

25 Figure 3 is a front elevation of the burner.

Referring to the drawings in detail it will be seen that the numeral 5 denotes a cylindrical casing formed in two sections *a* and *b* the former being longer than the latter. The section *b* is located below the section *a* and an interfitting joint *c* is provided therebetween. A bottom 6 extends across the bottom end of the section *b*. A fuel pipe 7 extends through an opening in the section *b* and terminates above the center of the bottom 6. The section *a* is perforated with a plurality of annular series of perforations 8. A concavo-convex vaporizer plate 9 has its concave face disposed upwardly and is provided with a plurality of outwardly diverging legs 10 at the 30 edge thereof. The pipe 7 extends between a pair of these legs and terminates below the center of the plate 9. The upper edge of the section *a* is widened outwardly and inwardly to provide a bead 11. From the inner portion of the bead 11 depends a skirt 12 a slight distance down into the section *a* and this functions as a down draft reflector and further assists in mixing the air with the fumes and also reflects more heat on the vaporizer and maintains such intense heat in the burner so as to consume carbon and provide a perfect flame. Numeral 13 denotes an upwardly and outwardly flared collar extending to the sides of the stove and the lower edge thereof is provided with an inturned flange 14 extending under the outward portion of the bead 11.

To start the burner it is necessary to first heat the vaporizer plate 9. This can be done by a small bit of paper or other substance held under the plate. When this plate is sufficiently hot the preheated fuel passes in through the pipe 7 5 and is ignited.

It is thought that the construction, utility and advantages of this invention will now be quite apparent to those skilled in this art without a more detailed description thereof.

10

The present embodiment of the invention has been described in considerable detail merely for the purposes of exemplification since in actual practice it attains the features of advantage enumerated as desirable in the statement of the 15 invention and the above description.

It will be apparent that changes in the details of construction, and in the combination and arrangement of parts may be resorted to without departing from the spirit or scope of the invention 20 as hereinafter claimed or sacrificing any of its advantages.

Having thus described my invention, what I claim as new is:

1. A burner of the class described comprising a 25 cylinder having plain interior and exterior walls, the cylinder having a plurality of annular rows of perforations therein, the bottom row being located an appreciable distance from the bottom of the cylinder, a ring-shaped enlargement at the top of the cylinder having a portion projecting inwardly from said top, a short depending skirt connected with said inner portion of the enlargement, the skirt being spaced from the top of the cylinder and the top row of perforations opening 30 out into the space, the lower end of the cylinder being closed, a plate having downwardly and outwardly sloping leg portions connected therewith, the lower ends of which rest on the bottom 35 of the cylinder, and a fuel pipe passing through a portion of the side wall of the lower part of the cylinder and terminating under the plate.

2. A burner of the class described comprising a cylinder having plain interior and exterior walls, the cylinder having a plurality of annular 45 rows of perforations therein, the bottom row being located an appreciable distance from the bottom of the cylinder, a ring-shaped enlargement at the top of the cylinder having a portion projecting inwardly from said top, a short depending 50 skirt connected with said inner portion of the enlargement, the skirt being spaced from the top of the cylinder and the top row of perforations opening out into the space, the lower end of the cylinder being closed, a plate having downwardly 55

and outwardly sloping leg portions connected therewith, the lower ends of which rest on the bottom of the cylinder, a fuel pipe passing through a portion of the side wall of the lower part of the cylinder and terminating under the plate, said plate having a convex lower face and

the cylinder being formed of a short lower section and a long upper section, with the lower row of perforations arranged adjacent the lower end of the upper section.

HARVEY C. GORE.
